UNITED STATES PATENT OFFICE.

GUS. W. RICHARDSON, OF HILL GROVE, KENTUCKY.

AGITATOR OR EGG-BEATER.

SPECIFICATION forming part of Letters Patent No. 252,800, dated January 24, 1882.

Application filed December 20, 1881. (No model.)

To all whom it may concern:

Be it known that I, GUS. W. RICHARDSON, of Hill Grove, in the county of Meade and State of Kentucky, have invented a new and Improved Agitator or Egg-Beater; and I do hereby declare that the following is a full, clear, and exact description of the same, reference being had to the accompanying drawings, forming part of this specification, in 10 which—

Figure 1 is a side elevation, partly in section, of my improved agitator or egg-beater. Fig. 2 is a side elevation of the agitator-wheels. Fig. 3 is a plan view of the base-flange, and 15 Fig. 4 is a plan view of the agitator-wheels.

My invention relates to improvements in agitators or egg-beaters; and it consists in the peculiar construction and arrangement of the parts, as hereinafter more fully set forth.

20 In the accompanying drawings, *a* represents a circular vertical flange or annulus, provided with the cross-bars *b b* at right angles to each other, and secured to the inner face of the flange *a* at their outer ends and to each other 25 at the center of the annulus or flange *a*. The cross-bars *b b* are diameters of the annulus or flange, and serve as beaters in the vertical reciprocations of the device, as hereinafter set forth, and also at their junction with each 30 other serve as a support for the hollow vertical step *c*, in which the lower end of the vertical shaft *d* of the agitators has its lower bearing, the upper end of the agitator-shaft *d* having its bearing in a hole in the lower end 35 of the handle *e*.

h represents an agitator composed of an outer vertical flange or ring, *h'*, a hub, *h²*, provided with a central hole for the passage of the agitator-shaft *d*, and radial vanes *h³*, all inclined at the same angle, the outer ends of the vanes *h³* being secured to the inner circumference of the vertical flange *h'*, the inner ends of the vanes being secured to the hub *h²*.

i represents a short cylinder provided with 45 a central longitudinal hole or opening. The cylinder *i* is slipped on the agitator-shaft *d*, its lower end resting on the hub *h²* of the agitator *h*, and its upper end supporting the upper agitator, *k*, of precisely the same construction as 50 the lower agitator, *h*, excepting that its diameter

is less and its vanes are inclined in an opposite direction, so that in the vertical reciprocations of the cone the agitators will revolve in opposite directions.

l represents a cone, provided with a circular vertical flange or base, *l'*, of slightly greater diameter than the circular flange *a*, and having angular recesses *l²*, forming a bayonet-fastening, with pins *m* secured to the sides of the circular vertical flange *a*. By this construction 55 the cone *l* can readily be secured to and detached from the annulus or flange *a*, and the agitators removed for cleaning them or other purposes. The circular base-flange *l'* and the cone *l* are provided with a series of openings, 60 *l³*, leading into the agitators *h k* and into the interior of the cone.

n represents a tube inserted in a circular hole made in the apex of the cone. The tube *n* is open at both ends, and extends a short 70 distance above the apex of the cone and down into its interior, and is supported by a horizontal diaphragm secured to the interior of the cone and tube *n*.

The handle *e* is made to fit into the tube *n* 75 and extends to the lower end of said tube, and is provided at its lower end with a hole which serves as a bearing for the upper end of the agitator-shaft *d*, as before described. By the employment of a cone in lieu of a cylinder, as heretofore employed, the handle is braced from every direction, and the cone can more readily be raised in the fluid in which it vertically reciprocates than if made cylindrical, and the parts are easily separated for 80 cleaning or other purposes.

What I claim as my invention is—

The combination, with the perforated cone *l*, provided with the perforated base-flange *l'*, having angular recesses *l²* and tube *n* at its 90 apex for the reception of the handle *e*, of the annulus *a*, provided with the pins *m*, and cross-bars *b*, supporting the step *c*, and agitators *h k*, adapted to revolve in opposite directions, substantially as described, and for the 95 purpose set forth.

GUS. W. RICHARDSON.
